UNITED STATES PATENT OFFICE

OSCAR W. GORENFLO, OF BUFFALO, NEW YORK

STOVEPIPE VENTILATING THIMBLE

Application filed February 7, 1929. Serial No. 338,312.

This invention relates to stove pipe ventilating thimbles. Devices of this character as heretofore made and used have been constructed of heavy metal castings requiring the making of a substantial number of individual castings subsequently assembled by bolts, nuts, rivets and the like to form the ventilating thimble, in which the exposed portion of the ventilating thimble viewed from the room or other place where it is positioned has an exposed flange and ears through which anchoring screws or bolts are positioned in order to mount the ventilator in position on a wall over the chimney opening so it will support a stove pipe. This sort of construction has presented many difficulties both in the making of the parts, the assembly of the parts and the mounting of the ventilating thimble on the wall which requires an unusual amount of time and labor in order to properly place the support for the stove pipe and the ventilating thimble in position over the chimney opening in the wall. It is customary in most instances to make the opening communicating with a chimney through a wall much larger than the pipe from the stove which is to enter the chimney and in making a device of this character provision must be made for covering up the unsightly appearance resulting from the difference in size between the opening in the wall and the stove pipe.

The present invention overcomes substantially all of the disadvantages of these prior constructions and provides a simple and efficient construction which may be placed in position without the use of any securing screws or bolts or other similar means in the opening in a wall communicating with a chimney, which will provide a means for receiving a stove pipe of smaller diameter than the opening in the wall and at the same time provide a spacing plate to cover the opening between the pipe and the wall which also takes advantage of this opening to secure ventilation of the room with which it communicates so as to make a neat finish on the wall adjacent to the opening and around the pipe.

The invention comprehends the provision of a three-part structure in which the three

parts are rigidly connected together including a sleeve member adapted to fit the standard size of opening usually placed in the wall communicating with the chimney which will support the ventilating thimble of this invention by insertion of the sleeve into the opening, a ring secured to the sleeve and seating against the wall around the opening and a facing member being provided for concealing all of the other parts of the invention from view and providing a neat appearing structure against the wall around the opening which is provided with an opening to receive the stove pipe and center it in the opening in the wall communicating with the chimney and which is also provided with openings adapted to permit the draft in the chimney to withdraw the air from the room and thereby provide ventilation in the room.

The specific construction of the invention and other features of novelty are more particularly pointed out in the following detailed description and in the claims directed to the preferred form of construction, it being understood, however, that various changes may be made in the specific relation between the parts without departing from the spirit or the scope of the invention as herein described and claimed.

In the drawing forming part of this application,

Fig. 1 is a perspective view showing the invention applied in the chimney opening in a wall and showing a stove pipe extending through the facing member thereof for communication with the chimney.

Fig. 2 is a central longitudinal section through the improved stove pipe ventilating thimble showing portions in elevation.

The improved stove pipe ventilating thimble comprising the invention is formed entirely of sheet metal and includes a sheet metal sleeve 1 having the free end 2 corrugated to produce a slightly reduced end in the usual manner well known in the art so that the sleeve will readily enter and slidably engage in the opening in a wall communicating with a chimney. The opposite end of this sleeve 1 is provided with an inwardly extending fold portion 3 terminating in an out-

wardly extending fold portion 4 spaced slightly from the portion 3 to provide an outwardly facing annular channel which receives the inner edge of the sheet metal ring 5. The portions 3 and 4 are firmly engaged with the inner edge of the ring 5 about which they are formed in assembling the sleeve and the ring. This ring 5 extends radially outward as clearly shown in Figure 2 of the drawings and a facing member 6 of frusto-conical form as shown in Figure 2 has its outer edge formed around the outer marginal edge of the ring 5 to provide the portions 7 and 8 engaging the outer edge of said ring so as to rigidly connect said facing member with the outer edge of the ring. The facing member is otherwise spaced from the ring and sleeve as illustrated in Figure 2 and is formed with a central opening 9 of smaller diameter than the sleeve 1 and of a size to slidably receive the usual standard size of stove pipe used with gas ranges and other types of cooking and heating stoves for houses and apartments. The inner edge of the facing member 6 adjacent the opening 9 is provided with a rounded section indicated at 10 terminating in an inwardly or rearwardly directed cylindrical portion 11 which extends towards the sleeve 1 and forms a pipe supporting portion. The rounded portion 10 facilitates the insertion of a stove pipe 12, as shown in Figure 1 in full lines, and in dotted lines in Figure 2, into the opening 9 for sliding movement through the portion 11 so that the end of the pipe 12 will terminate adjacent to the free end of the sleeve 1, for example, as illustrated in Figure 2 in dotted lines.

The facing member is formed around the central opening 9 and in spaced relation thereto with a plurality of small openings 13 which form ventilating openings.

By the above described construction a stove pipe ventilating thimble is provided which is formed of three parts rigidly assembled together in the manner described and illustrated which may be readily applied in the opening in a wall of a dwelling or other building provided for a stove pipe, the sleeve having the free end inserted in this opening which it is constructed to slidably fit. This sleeve is entirely inserted into the opening so that the ring 5 engages the face of the wall adjacent the opening as a result of which the facing member 6 is the only part exposed to view after this stove pipe support and ventilating thimble is applied in the opening in the wall. Then the stove pipe is inserted through the opening 9, the rounded portion 10 facilitating the engagement of the end in the opening, so that the end will extend into the sleeve 1 and terminate in a position adjacent the part where the opening in the wall communicates with the chimney as a result of which the draft in the chimney will draw the fumes and vapors from the stove pipe into and up the chimney

for discharge in the usual manner. This stove pipe will be spaced from the sleeve 1 thereby providing an annular passage around the pipe into the chimney with which the openings 13 communicate so that the draft in the chimney will also create a suction in this annular space, to draw the air in the room through the openings 13 and up the chimney, thereby ventilating the room at all times. This ventilating thimble is of particular value to housewives for use in the kitchen whether gas ranges, electric ranges or other stoves are used in order to ventilate the kitchen and withdraw the vapors and fumes from cooking continuously so that they are not distributed in other parts of the dwelling. By making the parts of sheet metal together with the special manner of assembly as above described provides a simple and easily manufactured pipe support and ventilating thimble which may be made and sold at a very reasonable price and which does not require any special labor, bolts, nuts, screws, tools or any other parts to support the device, and which requires nothing but the slidable insertion of the sleeve 1 into the opening in the wall to mount the device in operative position.

This invention greatly improves prior practices in the art because it eliminates the use of reducing thimbles and face plates for stove pipes and in addition adds the ventilating feature in a single unitary structure, that is, it performs a three-fold purpose.

What is claimed is:

1. A stove pipe ventilating thimble comprising a sheet metal sleeve, a sheet metal ring, one end of said sleeve being formed to provide fold portions engaging the opposite sides of the inner edge of said ring and rigidly connecting said sleeve and ring, and a sheet metal facing member of frusto-conical form having its outer edge formed to provide an inwardly facing channel receiving the outer edge of said ring and rigidly connecting said ring and facing member, said facing member having a central opening and having the marginal portion adjacent said opening formed to provide a curved section terminating in a cylindrical pipe supporting portion extending toward said sleeve and of smaller diameter than said sleeve, said curved section being adapted to guide a pipe into said pipe supporting portion, and said facing member having a plurality of ventilating openings formed between the inner and outer edges thereof.

2. A stove pipe ventilating thimble comprising a sheet metal sleeve, a sheet metal ring, one end of said sleeve being formed to provide fold portions engaging the opposite sides of the inner edge of said ring and rigidly connecting said sleeve and ring, and a sheet metal facing member having its outer edge formed to provide an inwardly facing

channel receiving the outer edge of said ring and rigidly connecting said ring and facing member, the remaining portions of said facing member being spaced from said ring and having a central pipe receiving opening and a plurality of small spaced openings formed therein, said pipe receiving opening having a smaller diameter than said sleeve and being substantially in axial alignment therewith.

10 3. A stove pipe ventilating thimble comprising a sheet metal sleeve, a sheet metal ring having its inner edge rigidly connected to one end of said sleeve, and a sheet metal 15 facing member having its outer edge rigidly attached to the outer edge of said ring and the remaining portions spaced from said ring, said facing member having a laterally extending flange defining a central opening of 20 smaller diameter than said sleeve and aligned therewith, and having ventilating openings therein spaced around said central opening.
